UNITED STATES PATENT OFFICE.

WILLIAM A. VOSPER, OF ARLINGTON, NEW JERSEY.

METHOD OF MAKING STITCH-DOWN SHOES.

1,146,825.

Specification of Letters Patent. Patented July 20, 1915.

Application filed June 27, 1914. Serial No. 847,607.

To all whom it may concern:

Be it known that I, WILLIAM A. VOSPER, a citizen of the United States, residing at Arlington, county of Hudson, and State of New Jersey, have invented a certain new and useful Method of Making Stitch-Down Shoes, of which the following is a specification.

The invention is a method of making 10 stitch down shoes.

The objects in view are to conceal the clenched or upset ends of the staples by which the upper is fastened to the sole; to simplify and expedite the operation of 15 making the shoe, incidentally attaining economy of manufacture, and to build up the heel portion of the shoe while utilizing a single sole in the manufacture of the article.

The salient feature of the invention is a 20 sole the edge portion of which is split around the toe and at the sides, thus producing a one-piece sole with a divided edge portion. The upper is lasted for its edge to turn outwardly and overlap the split part of the 25 sole, and at this time the upper and sole are united by permanent fastenings, preferably in the form of wire staples the ends of which pass through the out-turned edge of said upper and one part of the divided sole. The 30 points or ends of the staples are upset or clenched against that part of the divided sole through which the staples are passed, and the other part of the sole is leveled down or flattened in any suitable way so that the 35 channeled part of the sole is closed, as a result of which the clenched parts of the staples are incased within the divided part of the sole and thus concealed from view thereby.

It is to be understood from what has been said that the process involves the following 40 procedure: channeling the sole around the toe and side portions thereof; imposing said sole upon a last; lasting an upper; uniting 45 the upper and the channeled part of the sole by permanent fastenings such as staples the ends of which are clenched within the channeled part of the sole, and closing said channeled part of the sole and upon the clenched 50 ends of the staples by leveling the sole.

Another part of the invention is a built up heel portion the characteristic feature of 55 which is a divided heel part of the sole within which is positioned one or more heel lifts, the interposition of which depresses the heel part of the sole below the level of the instep and foot part of said sole, the whole being

fastened firmly together by appropriate means.

Other features and advantages of the invention will appear from the following detailed description.

In the drawings, Figure 1 is a perspective view illustrating the operation of lasting the shoe, the under split part of the sole being turned to an abnormal position to illustrate the clenching of the staples against the upper split part of the sole. Fig. 2 is a side elevation illustrating the complete shoe. Fig. 3 is a vertical longitudinal section 70 through the shoe of Fig. 2, and Fig. 4 is a vertical transverse section through the foot part of the shoe.

A designates the sole, B the upper, and C the heel of a shoe embodying this invention. 75

An important feature of the invention is the construction of sole A. At the toe and side portions of the sole it is split or divided, the line of division or split being indicated at a. As a result of this division of the sole 80 it is provided with an upper lip b and a lower lip c. The heel part of the sole is divided longitudinally and centrally thereof, the line of division being indicated at d. This division line d extends entirely across 85 the sole from side to side thereof and from the rear edge of the heel portion to the shank of the sole, all as clearly shown in Fig. 3. By thus dividing the heel portion of the sole at d there results two members e f integral 90 with the sole, the purpose of which will presently appear.

As is usual in shoes of this character, the edge portion of upper B is turned outwardly, thereby producing a flange g. This flange 95 extends around the entire edge portion of the upper, and it is in contact with the lip b and the member e of the sole. The flange of the upper and the sole A are united by permanent fastenings D, the same being shown 100 herein as staples. These staples pass through the flange g of the upper and the lip b and member e of sole A. The staples are upset or clenched against the under face of lip b and member e of said sole, thereby 105 permanently attaching the upper to the sole. Subsequent to the operation of stapling the upper and the sole together the lower lip c of the sole is closed relative to the upper lip b thereof, and the heel is built up, as will 110 presently appear, so that the clenched ends of the staple fasteners will all be concealed from view by certain parts which are integral with the sole.

In the manufacture of a shoe in accordance with my invention it is preferred to build up the heel portion so that the under face of the heel is in a different plane from the foot portion of the sole. Accordingly, the rear portion of the sole is divided at *d*, as heretofore described, and within this divided part is positioned one or more heel lifts *E*, whereby said heel lifts are interposed between the members *e f* of the divided rear part of the sole. It will be understood that the member *e* of the sole is stapled to the upper, but the member *f* of said sole, together with the heel lift or lifts *E* are fastened to the shoe by attaching means separate from the staples *D*, said attaching means being shown as nails *h*. It is preferred to employ within the shoe at the heel thereof another layer of material *F*, and the nails *h* are driven through the sole member *f*, the heel lift *E*, the sole member *e* and the lining part *F*, whereby the heel is attached rigidly to the sole and the upper.

In the manufacture of the shoe I proceed as follows: The sole *A* is first channeled, split, or divided along the toe and side portions, and the rear or heel part of the sole is split entirely through the same as heretofore mentioned. Said sole is now imposed upon the last to which it is fastened in the usual way by the lasting tacks. The upper is drawn over the last and the edge portion of said upper is turned outwardly to form the lip *g* which in the operation of lasting the upper is imposed firmly upon and in contact with the edge portion of the sole around the toe, heel and side portions. The upper is now fastened permanently to the sole by the staples *D* passing through the flange of the upper and the lip *b* and member *e* of the sole.

Prior to the operation of stapling the upper, the lower lip *c* of the sole is turned down, Fig. 1 illustrating said lip *c* in the turned down position. During the operation of stapling the upper, a suitable tool is positioned opposite to the ends of the staples so that they will be clenched against the tool. Subsequent to lasting and stapling the upper and the sole, the division *a* of said sole is closed by pressing the lip *c* toward the lip *b*, and in practice this closing of the divided part of the sole is obtained by leveling the sole, the pressure of the leveling mechanism being exerted to press the lip *c* against the lip *b* and the clenched ends of the staples. It is thus apparent that the upset or clenched ends of the staples are covered by the lip *c* when the sole is leveled.

The heel portion of the shoe is built up by interposing one or more lifts between the members formed by the divided rear part of the sole, and, finally, fasteners *h* are

driven through the heel so as to attach the member *f* of the sole and the heel lift or lifts to the rear of the shoe. Of course, the upper is trimmed and the shoe is finished in any manner usual in the art.

Having thus fully described the invention, what I claim as new, and desire to secure by Letters Patent is:

1. The process of making stitch down shoes which consists in splitting the marginal portion of a sole to form upper and lower marginal flaps, imposing said sole upon a last, bending the lower marginal flap away from the upper marginal flap, lasting an upper and turning out the lower marginal portion of said upper upon the upper surface of said upper flap, passing staples through the outturned portion of said upper and through said upper flap and clenching their points against the lower surface of said upper flap, and leveling the sole to close the lower flap upon the upper flap.

2. In the art of making stitch down shoes, the process which consists in splitting the marginal portion of a sole by a cut extending parallel to the top and bottom surfaces of the sole to form upper and lower marginal flaps each of appreciable uniform thickness, imposing said sole upon a last, lasting an upper and turning out the marginal portion of said upper into contact with the upper marginal flap of the sole, bending the lower flap away from the upper flap and stapling the lower marginal portion of the upper against the upper flap of said sole, the points of said staples being clenched against the upper flap, and leveling the sole to close the lower flap against the upper flap and the clenched ends of the staples for concealing the same.

3. The process of making stitch - down shoes which consists in splitting the marginal portion of a sole by a cut extending for a definite distance inwardly from the edge thereof and in dividing the heel portion of said sole by a cut extending for a certain distance forwardly from the rear edge and extending also from side to side of the sole, imposing the sole upon a last, lasting an upper, stapling the upper directly to one part of the split margin of the sole and clenching the staples against said split marginal portion, building up the heel by inserting a lift within the divided heel portion of the sole, and closing the split marginal portion and the divided heel portion of said sole.

In testimony whereof I have signed my name to this specification in the presence of two subscribing witnesses.

WILLIAM A. VOSPER.
